CLAIM

We claim the ornamental design for a print indicia and address label sheet, as shown and described.

DESCRIPTION

FIG. 1 is a front view of a print indicia and address label sheet showing our new design;

FIG. 2 is a side view thereof, it being understood that the opposite side is a mirror image thereof;

FIG. 3 is a bottom view thereof, it being understood that the top view is a mirror image thereof; and,

FIG. 4 is a rear view thereof.

The broken lines shown in FIG. 1 and FIG. 4 of the drawing represent perforation lines.
